CLAIM

The ornamental design for a portable data terminal, as shown and described.

DESCRIPTION

FIG. 1 is a bottom, front, and left side perspective view of a portable data terminal;

FIG. 2 is a bottom, rear and right side perspective view of the portable data terminal shown in FIG. 1;

FIG. 3 is a bottom perspective view of the portable data terminal shown in FIG. 1;

FIG. 4 is a front view of the portable data terminal shown in FIG. 1;

FIG. 5 is rear view of the portable data terminal shown in FIG. 1;

FIG. 6 is a bottom view of the portable data terminal shown in FIG. 1;

FIG. 7 is a top view of the portable data terminal shown in FIG. 1;

FIG. 8 is a left side view of the portable data terminal shown in FIG. 1; and,

FIG. 9 is a right side view of the portable data terminal shown in FIG. 1.

The broken lines are shown in the views for illustrative purposes only and form no part of the claimed design.
